UNITED STATES PATENT OFFICE.

OTTO KNOERZER AND JOSEPH W. WEIS, OF HAMMOND, INDIANA; SAID KNOERZER
ASSIGNOR TO SAID WEIS.

COMBINED MEMORANDUM-PAD SUPPORT AND LIGHTING DEVICE.

1,030,825.

Specification of Letters Patent. Patented June 25, 1912.

Application filed April 17, 1911. Serial No. 621,600.

To all whom it may concern:

Be it known that we, OTTO KNOERZER and JOSEPH W. WEIS, citizens of the United States, residing at Hammond, in the county of Lake and State of Indiana, have invented new and useful Improvements in Combined Memorandum - Pad Support and Lighting Devices, of which the following is a specification.

10 This invention relates to a new and improved combined memorandum pad support and lighting device and has for its object to provide a memorandum pad support in combination with electric lighting means for illuminating the surface of the pad carried by the support, whereby an illuminated surface may be presented in an otherwise dark room or place, upon which memoranda may be written.

20 Another object is to provide a device of this character with means for detachably supporting it in convenient position upon a support such as a bedstead, chair or the like.

It frequently happens that thoughts or 25 ideas are developed at times when it would be very advantageous to register or record them, that is, to make a memorandum thereof for future reference. Many brainy men do a great deal of thinking after retiring 30 for the day, and the convenience of having a self illuminating device upon which the thinker may make a memorandum of his thoughts or ideas is self evident.

This invention has been designed to produce a simple device of this character, and to such ends the invention consists in a memorandum pad support, arranged to support an electric battery and having a small incandescent lamp associated therewith and arranged to reflect light upon the surface of the pad to be written upon. The invention further consists in the details of construction, combinations and arrangements of parts hereinafter set forth and claimed.

45 The invention is clearly illustrated in the drawing furnished herewith, in which:—

Figure 1 is a perspective view of a combined memorandum pad support and lighting device embodying our improvements, Fig. 2 is a section taken on the line 2—2 of Fig. 5, Fig. 3 is a section taken on the line 3—3 of Fig. 5, Fig. 4 is an end view looking in the direction of the arrow 4 in Fig. 5 and Fig. 5 is a longitudinal section through the 55 device.

In the drawings 10, represents a memorandum pad support, here shown in the form of a flat rectangular plate 11, having an upturned flange 12, along one side, and an upwardly curved flange 13, at one end. Secured to the support at its upper end is a battery case 14, having four sides and two ends. The battery case may be secured to the support by soldering its lower side 15, to the flanges 12, 16, of the supporting plate 11. One end 17, of the case is preferably secured rigidly to the side walls thereof, but the other end 18, is removably secured thereto in order that the interior may be readily accessible. In the simple form shown, the ends 17, 18, are flanged to fit upon the ends of the sides of the case. The case is shown of rectangular form, but obviously it may be made of any suitable form or shape, as desired.

75 Within the case is an electric battery 19, held therein by friction with the walls and arranged to light a small incandescent electric lamp 20, removably secured in a socket 21, that projects out from the side of the case that extends upward from the pad. The socket flares outwardly as seen in 22, to partly shade the lamp and to direct the rays of light toward the pad, whereby it may be illuminated when the light is turned on. 85 The lamp makes an electric contact with the metal case through its engagement with the socket 21, and also makes an electric contact with the metal body of the battery as at 24. Said battery is insulated from the metal 90 case by a wrapper 25, of insulating material, which wrapper is cut away at 26, to expose the metal body of the battery for contact with the point 24, of the lamp. A stop 29, spaces the end of the battery 19, away from the end wall 17. In this space is contained 95 means for making and breaking the circuit between the battery and lamp.

A metal push button 28, is carried by the end wall 17, of the case and is arranged to make contact with a contact piece 27, of the battery. The push button acts as a contact piece whereby when said push button is pushed inward a circuit is made through the battery, the lamp and the case. The location 105 of the push button 28, is of some importance because with the arrangement shown in the drawing the device may be held in the hand and the push button pressed with one of the fingers of the hand holding the device, while 110

the other hand may be used to write upon the pad.

An opening 30, is formed in the upper end of the flange 12, and in the space between the case and plate 11, of the holder 10, is secured a flat spring 31, which is arranged to secure a pencil P, in the holder. The flat spring 31, is soldered or otherwise secured to the flange 12, of the plate 11, and is arranged to be pressed back whenever a pencil is thrust in through the opening 30, the tendency of the spring being to frictionally hold the pencil between the flange 13, of the plate and the spring.

In order that the register may be detachably carried by a bedstead or the like, so as to be in convenient position to be reached when one has retired, we provide means for detachably securing it to such a bedstead or other support. One form of the detaching means comprises a wire hook 33, secured at the top of the device and arranged to hook over any horizontal rod such as the cross rod of a bedstead. The form of hook shown has two legs that extend in through holes in the wall of the case and are bent outward to engage with the wall when the hook is drawn to its outward position. It may be pushed back so as to be partly closed within the case when not in use.

Another form of securing means comprises a clip 34, lying underneath the plate 11, and secured to the flange thereof by hooks 36, the clip being wound into the form of coil springs 35, between its ends that act to press the long arm of the clip toward the plate 11. This clip provides means whereby the device may be detachably secured upon a vertical support such as a post or the like.

In using the device, a memorandum pad A, is inserted between the battery case and plate 11, and held therebetween by reason of the friction. The memorandum pad is scored along the line a, whereby the sheets may be torn off after they have been written upon. The device may be grasped in one hand and the push button pressed to make contact with the battery, closing the circuit through the battery and lamp and lighting the latter. The light from the lamp is thrown directly upon the upper surface of the pad so that the user may see to write thereon in an otherwise dark place. After using the device it may be hung upon the bedstead or other convenient place for future use.

It is obvious that in place of a memorandum pad, a memorandum book such as a guide book, may be carried by the device,

which book may be readily referred to in the dark by pressing the button and illuminating the book from the lamp.

We are aware that various alterations and modifications of this device are possible without departing from the spirit of our device, and we do not therefore wish to limit ourselves to the exact form of construction shown and described.

We claim as new and desire to secure by Letters Patent:

1. A combined memorandum pad support and lighting device comprising a memorandum pad supporting plate, a battery case secured thereto at one end, and spaced therefrom to receive a memorandum pad therebetween, said plate and case co-operating to grip said memorandum pad therebetween, and said case containing an electric battery, in circuit with an electric lamp, projecting out from the side of said case adjacent the pad, and arranged to illuminate said pad.

2. A combined memorandum pad support and lighting device, comprising a memorandum pad support, a battery case secured thereto at one end and co-acting with the support to grip a memorandum pad therebetween, an electric battery within said battery case and an electric incandescent lamp in circuit with said battery and supported by said case on its outer side, said lamp being arranged in position to illuminate a pad carried by the support.

3. A combined memorandum pad support and lighting device comprising a pad supporting plate, a battery case secured thereto at one end and spaced therefrom to receive a pad therebetween, said plate and case acting to grip said pad therebetween, an electric lamp projecting out from the side of the case adjacent the pad and adapted to illuminate the latter, an electric battery contained in said case, and a push button projecting out from one end of the case and arranged to make and break an electric circuit through the battery and lamp, the parts being so arranged and proportioned that the device may be held in one hand and the push button pressed by a finger of that hand to close the circuit.

In witness whereof, we have hereunto signed our names, at Hammond, Lake county, Indiana, this 12th day of April 1911.

OTTO KNOERZER.
JOS. W. WEIS.
